UNITED STATES PATENT OFFICE.

OSCAR KROEHLER, OF LAKEWOOD, OHIO.

SOCKET FOR INCANDESCENT ELECTRIC LAMPS.

1,386,412.

Specification of Letters Patent.

Patented Aug. 2, 1921.

Application filed February 17, 1921. Serial No. 445,777.

To all whom it may concern:

Be it known that I, OSCAR KROEHLER, a citizen of the United States, residing at Lakewood, in the county of Cuyahoga and State 5 of Ohio, have invented a new and useful Socket for Incandescent Electric Lamps, of which the following is a specification.

This invention relates to improvements in sockets for incandescent electric lamps, and 10 more especially to a socket of the character indicated which is adapted to be rendered rigid with a casing adapted to extend circumferentially of an incandescent electric lamp applied to the socket for illuminating 15 a signal lens or sign with which said casing is provided after the application of said lamp to the socket.

One object of this invention is to so construct and apply the socket that not only is 20 said casing adapted to be applied to the rear portion of a rear fender of a motor-vehicle, but that an arrangement of said casing in desirable proximity to said fender is permitted.

25 Another object is to have the contacts or terminals of the socket and the contacts or terminals of the base of a lamp connected to the socket adequately protected against the weather and against injury, and to exclude dust and dirt from said contacts or 30 terminals.

Another object is not only to produce a short socket of the character indicated and to protect the contacts of the socket by a 35 removable cap, but to have the construction of the socket such that said cap requires little room for detaching it from or applying it to the body of the socket.

Another object is to facilitate the assembly 40 of the component parts of the socket, and to render the socket simple and durable in construction, reliable in the performance of its functions, and not liable to get out of order.

45 With these objects in view, and to attain any other object hereinafter appearing, this invention consists in certain meritorious features of construction, and combinations and relative arrangements of parts, hereinafter 50 described in this specification, pointed out in the claims, and illustrated in the accompanying drawings.

In said drawings, Figure 1 is a vertical

section taken through a portion of a rear fender of a motor-vehicle and shows said fender 55 provided with a bracket from which is supported a lamp-socket embodying my invention. Fig. 2 is a vertical section taken along the line 2—2, Fig. 1. Fig. 3 is a view which, in the main, is a horizontal section taken 60 along the line 3—3, Fig. 1. Fig. 4 is a vertical section, in detail, taken along the line 4—4, Fig. 1. Fig. 5 is a view corresponding with Fig. 4, except as to the position of the movable part illustrated in Figs. 4 and 5. 65 Fig. 6 is a vertical section, in detail, taken along the line 6—6, Fig. 1. Fig. 7 is a section taken along the line 7—7, Fig. 6. Fig. 8 is a section taken along the curved line 8—8, Fig. 6. Fig. 9 is a section 70 taken centrally through my improved lamp-socket without the cap for the socket. Fig. 10 is a section taken along the line 10—10, Fig. 9. Fig. 11 is a section taken along the line 11—11, Fig. 10. Figs. 4, 5, 6, 75 7, 8, 9, 10 and 11 are drawn on a larger scale than Figs. 1, 2 and 3.

Referring to Figs. 1 and 3 of said drawings, 15 indicates the rear portion of a rear metal fender of a motor-vehicle, and 16 80 (Fig. 1) indicates a metal bracket projecting rearwardly and upwardly in relation to and supported from said fender. A metal casing 17 is supported from said bracket and extends farther from the bracket in the direction of the fender 15 than in the opposite direction. Said casing is considerably larger in diameter at its outer end than at its inner end and flares toward its diametrically larger or outer end. Said casing 85 (See Fig. 1) is provided at its diametrically larger or outer end with a lens 18 which is removably secured in place in any approved manner. Said lens is arranged in a vertical position and faces rearwardly in relation to 90 the vehicle, for the purpose of indicating or signaling, to drivers of following vehicles upon the required illumination of the lens at the inner side of the lens, that movement of the signaling vehicle is being slowed or 100 about to be arrested. Obviously the lens, were it composed of light-transmitting red glass, would indicate danger upon the required illumination. An incandescent electric lamp, having its glass bulb 19 arranged internally of the casing 17, is em- 105

ployed in illuminating the lens 18, and said lamp is applied at its base to the hereinafter described socket, and said base (see Fig. 3) comprises an outer circumferentially extending metal shell 20 forming one of the terminals of said base and embracing a body of insulating material 21 which insulates said shell from the other or central terminal-forming contact 22 of said base, and the last mentioned contact protrudes at the outer end of said base.

The casing 17 (see Figs. 1, 3 and 9) is provided at its diametrically smaller or inner end and internally with an annular flange 23 the internal diameter of which measures enough more than the external diameter of the hereinbefore mentioned lamp-base to permit the application and removal of said base through the space surrounded by said flange.

My improved socket comprises an externally circular insulating body 25 arranged externally of the casing 17 at the outer side of and concentric in relation to the flange 23 and secured in place as will hereinafter appear. The insulating body 25 has a central opening 26 which registers with the space surrounded by the flange 23 and extends through said body endwise of the socket. Said opening has the dimensions and contour required to permit the hereinbefore mentioned lamp-base to extend endwise therethrough, and in Figs. 1 and 3 said base is shown extending through said opening.

The insulating body 25 abuts at its inner end face against the flange 23, and a rigid tubular metal shell 27 is arranged at and preferably abuts against the opposite end face of said body. The shell 27 is diametrically smaller than the insulating body 25 and in line endwise with and concentric in relation to the opening 26, and has the dimensions, contour and arrangement required to receive the hereinbefore mentioned lamp-base through said opening. The shell 27 forms one of the contacts of my improved socket, and a metal plate 28, which is applied as will hereinafter appear and insulated from said shell, forms the other contact of said socket and has a resilient member 30 extending opposite and spaced from the outer end of said shell and yieldable endwise of the socket. Said resilient member 30 is arranged to be pressed or moved somewhat outwardly, against the action of its resilience, by the central contact 22 of the lamp-base during the insertion of said base into place within the socket comprising the insulating body 25 and the shell 27. In Figs. 1, 2 and 3 said base is shown inserted into place within said socket. Figs. 1 and 3 show the terminal-forming shell 20 of said base as having a snug sliding fit internally of the

engagement with said socket-member. Figs. 1 and 3 show the central contact 22 of said base in electrical engagement with the resilient member 30. It will be observed therefore that the metal shell or contact 27 of the socket is arranged to be electrically engaged by one of the terminals of the lamp-base, and is adapted to be electrically connected to one of the terminals of an electric battery (not shown) or other source of electrical energy 75 through the medium of a current-conducting wire 31 applied as will hereinafter appear, and that the other contact (28 and 30) of the socket is arranged to be electrically engaged by the other terminal of the lamp-base and adapted to be electrically connected, as will hereinafter appear, with the flange 23 and consequently with the casing 17 which is adapted to be electrically connected in any approved manner, and preferably 85 through the medium of an electrical connection comprising the bracket 16 and fender 15, with the other terminal of the aforesaid electrical source. Obviously therefore the electric circuit including the incandescent 90 electric lamp is broken when said lamp is removed from the illustrated socket, and that when the base of said lamp is in place within said socket, as shown in Figs. 1, 2 and 3, said circuit is closed as required to light 95 the bulb of the lamp and thereby to illuminate the signaling or sign-forming lens 18.

The metal shell 27 of the socket (see Fig. 9) is provided at its inner end, and consequently adjacent the outer end face of the 100 insulating body 25, with a circumferentially extending flange 32 abutting against said body. The insulating body 25 is provided at its outer end face with two integral tubular insulating projections 33 which are 105 substantially parallel with the shell 27 and spaced circumferentially of said shell and extend through the flange 32 and beyond the outer side of said flange. The flange 32 closely embraces the projections 33 so that 110 said projections prevent circumferential displacement of and support the shell 27 and positively maintain said shell in accurate alignment with the opening 26 in the insulating body 25. It will be observed therefore that the shell 27 has portions formed by the flange 32 and embracing the projections 33 at the inner extremities of said projections. Each projection 33 is closely embraced, at the outer side of said flange 32, by 115 a rigid insulating washer 35 which abuts against said side of said flange and is thick enough to extend beyond the outer end of said projection. Each projection 33 embraces the shank 36 of a bolt which is substantially parallel with the socket and has a head 37 arranged internally of the casing 17 and abutting against the inner side of the flange 23 of said casing. Obviously therefore each bolt-shank 36 extends through the 120 125 130

flange 23, through and from end to end of the insulating body 25 and through the projection 33 embracing said shank and through the insulating washer 35 embracing said 5 projection, and beyond the outer side of said washer. Each washer 35 (see Figs. 2, 9 and 11) extends to and embraces the adjacent portion of the shell 27 which is therefore reinforced externally by said washer, 10 and said shell prevents displacement of said washer circumferentially of the bolt surrounded by said washer. At the outer side of the insulating washer 35 on the shank 36 of one bolt (see Figs. 1, 3 and 9) is a nut 15 38 which is threaded onto said shank, and obviously, upon manipulating said nut during the assemblage of the parts as required to tighten it in relation to said washer, said washer, the flange 32 of the shell 27, the insulating body 25, and the flange 23 of the 20 casing 17 are clamped together by and between said nut and the head 37 of said bolt, but it will be observed (see Figs. 9, 10 and 11) that on the shank 36 of the other bolt is 25 mounted the contact-forming metal plate 28, and a nut 39 is threaded onto said shank at the outer side of said plate which is interposed between said nut 39 and the insulating washer 35 surrounding the last-mentioned bolt. Obviously, upon manipulating 30 the nut 39 during the assemblage of the parts as required to tighten it in relation to the plate 28, said plate, the adjacent washer 35, the flange 32, the insulating body 25 and the flange 23 are clamped together by and between 35 said nut and the head 37 of the last-mentioned bolt. The plate 28 is provided, between the nut 39 and the shell 27, with an integral wing 29 which projects in the direction of and beyond the outer end of said shell and terminates in the resilient member 30 of the contact comprising said winged plate. The plate 28 (see Figs. 9 and 11) has a flange 40 overlapping the adjacent portion 40 of an edge of the adjacent washer 35, and said edge and said flange are arranged to prevent displacement of said plate circumferentially of the bolt on which said plate is mounted. By the construction hereinbefore described it will be observed that the nut 38 on one bolt is spaced from the adjacent projection 33 and insulated by the contiguous washer 35 from the contact-forming shell 27, and that the contact-forming plate 28 on the shank of the other bolt is spaced from the adjacent projection 33 and insulated by the adjacent washer 35 from said shell. It will be observed also that the plate 28 is electrically connected, through 50 the medium of the nut 39 and engaging bolt, to the casing 17, and that the projections 33 insulate the shell 27 from the bolts and consequently from said casing.

The hereinbefore mentioned wire 31 (see Figs. 1 and 2) extends through a hole 41

which is formed in the insulating body 25 and extends from the outer circumference of said insulating body inwardly and toward the shell 27 and to the outer end face of said body, and is in electrical engagement 70 with the flange 32 of said shell and secured to said flange by a screw 42.

Accidental detachment of the lamp-base from the socket is prevented by the conventional bayonet joint formed between said base and the shell 27, and therefore said base, to detach it from the socket, has to be manipulated as required to give it a part of one complete rotation in the required direction as well as longitudinal movement. The 75 formation of bayonet joints is too well understood to require description in detail in this specification. Suffice it to state (see Figs. 1, 2, 6, 7 and 8) that preferably the contact-forming shell 20 of the lamp-base 80 is provided externally with two metal pins or projections 43 spaced circumferentially of said shell, and that said shell at each projection 43 has a slot 45 which extends circumferentially of said base in the required direction from said projection which abuts against the adjacent end wall of said slot and preferably also against the outer side of the flange 32, and the resilient member 30 acts to maintain the lamp-base in 85 position with said projection in contact with said flange and said wall, so that a very effective electrical connection between the members 20 and 27 at one end of said slot is insured. Each slot 45 extends at its opposite end to the inner extremity of the shell 27 and registers at said end with a groove 46 formed in the surrounding wall of the opening 26 in the insulating body 25 and extending from end to end of said body, as 90 shown in Fig. 7. Said groove also registers at the outer end face of said insulating body 25 with a slot 47 formed in the flange 32 and forming an extension of the adjacent slot 45 in the shell 27, and said slot 47 in said 95 flange and said groove 46 have the dimensions and arrangement required to permit the adjacent projection 43 to pass through said flange and through said insulating body during the application and removal of 100 the lamp-base from the socket.

My improved socket also comprises a removable protective cap 50 which (see Figs. 1, 2 and 3) has a snug sliding fit on and embraces the insulating body 25 and abuts 105 at its inner end against the casing 17 which forms a stop for limiting movement of the cap in sliding the cap onto said body. Preferably the relative contour and dimensions of the diametrically smaller end of the casing 17 and the inner end of the cap 50 are such that said cap not only abuts against said casing but closely embraces said end of said casing, and by this construction a desirable joint is formed between the cap and 110

said casing, and the internal flange 23 of said end of said casing is arranged wholly internally of the inner end portion of said cap as desired to effect a simple and compact assemblage of the parts. Said cap has the dimensions required to be spaced at its outer end from the resilient member 30 and to form a housing in which parts to be protected such, for instance, as the shell 27 and its flange 32, the washers 35, the nuts 38 and 39 and adjacent portions of the engaging bolts, the contact comprising the resilient member 30, and the outer end portion of the lamp-base, are inclosed and adequately protected by said cap against the weather and against accidental injury, and dust and dirt are excluded from said parts by said cap. Obviously by my improved construction little space is required between the cap 50 and the fender 15 for the removal and application of the cap. Improved means for preventing accidental detachment of the cap 50 from the insulating body 25 are provided and illustrated in Figs. 1, 2, 4 and 5, and comprise recesses 51 which are formed, at the outer circumference of the inner end face of said insulating body, in and spaced circumferentially of said body. Each recess 51 is enlarged at one end endwise of the insulating body 25, as at 52, so that at said end said recess extends to the outer end face of said body, and said recess is spaced between its enlarged end 52 and its opposite end from said face. The recesses 51 extend from their enlarged ends 52 circumferentially of the insulating body 25 in the same direction, and the bottoms 53 of said recesses extend from said ends of said recesses toward the outer circumference of said body in said direction and form inclines. The cap 50 is provided, internally and at each recess 51, with a projection 55 formed by an inwardly offset portion of the cap and tightly engaging the incline-forming bottom 53 of said recess. Fig. 4 shows the bottom 53 of a recess 51 tightly engaged by a projection 55, and Fig. 5 shows the cap as having been manipulated as required to loosen said projection in relation to said bottom. The relative arrangement of the parts is such that the cap 50 is free to be removed from the insulating body 25 upon rotating the cap in the direction and the extent required to bring its projections 55 into engagement with the hereinbefore mentioned enlarged ends of the recesses 51, and said enlarged ends of said recesses are large enough in dimensions to permit said projections to pass therethrough during the removal or application of the cap. Said cap has a slot 56 registering with the outer end of the hole 41 in the insulating body 25 and extending endwise of the cap and arranged to permit the extension of the wire 31 through said slot into said hole 41, and said

slot extends to the inner extremity of the cap to prevent interference by said wire with the removal of the cap.

What I claim is—

1. A socket for an incandescent electric lamp comprising an externally circular insulating body having an opening which extends through said body endwise of the socket and is adapted to receive the base of said lamp, a metal shell which is opposite one end face of said insulating body and arranged and adapted to receive said base through said opening and forms one contact of the socket, a resilient member insulated from said shell and participating in the formation of the other contact of the socket, and a removable cap embracing the aforesaid insulating body and housing said shell and said resilient member, said insulating body being provided at the outer circumference of its inner end face with a circumferentially extending recess which is enlarged at one end to the outer end face of said body and spaced from said outer end face between said enlarged end and its opposite end and has an incline-forming bottom which extends toward said circumference in the direction of the last-mentioned end of the recess, and the cap being provided internally with a projection engaging said bottom. 90

2. A socket for an incandescent electric lamp comprising an externally circular insulating body having an opening which extends through said body endwise of the socket and is adapted to receive the base of said lamp, a metal shell which is contiguous at one end to one end face of said insulating body and arranged and adapted to receive said base through said opening and forms one contact of the socket, a resilient member participating in the formation of the other contact of the socket, and a removable cap housing and spaced from said shell and said resilient member and embracing the aforesaid insulating body, said body being provided at its outer circumference with circumferentially spaced recesses having enlarged ends extending to the aforesaid face, said recesses extending from their enlarged ends circumferentially of the last-mentioned face in the same direction, the bottoms of said recesses extending toward the outer circumference of said insulating body in said direction, and the cap being provided internally with projections engaging said bottoms. 115

3. A socket for an incandescent electric lamp comprising an insulating body having an opening which extends through said body endwise of the socket and is adapted to receive the base of said lamp, a metal shell arranged and adapted to receive said base through said opening and forming one contact of the socket, and a resilient member participating 125

- in the formation of the other contact of the socket and insulated from said shell and adapted to be electrically connected to one of the terminals of a source of electrical energy, and a removable cap surrounding and spaced from and housing said shell and said resilient member and embracing the aforesaid insulating body, said body having a hole extending from the outer circumference of said body inwardly and toward said shell to receive a current-conducting wire adapted to be employed in electrically connecting said shell with the other terminal of said electrical source, said cap having a slot which extends endwise of and to the inner extremity of the cap and is arranged to permit the extension of the aforesaid wire into the aforesaid hole from the exterior of the cap.
- 20 4. A socket for an incandescent electric lamp comprising an insulating body having a central opening which extends through said body endwise of the socket and is adapted to receive the base of said lamp, a metal shell which is arranged in line endwise with and concentric in relation to said opening and smaller diametrically than and held to said insulating body and arranged and adapted to receive the aforesaid base through said opening and forms one contact of the socket, and a resilient member insulated from said shell and participating in the formation of the other contact of the socket, said shell being provided at the adjacent end face of the aforesaid insulating body with an external circumferentially extending flange abutting against said face, and said body having projections which are spaced circumferentially of said shell and project into and are embraced by said flange.
- 25 5. In combination, an insulating body having an opening adapted to receive the base of an incandescent lamp, a metal shell which is in line endwise with said opening and adapted to receive said base through said opening and forms one contact of the socket, said insulating body having projections which are substantially parallel with and spaced circumferentially of said shell, and said shell having portions embracing the inner end portions and said projections, of rigid insulating members embracing the outer end portions of said projections and extending to and embracing the adjacent portions of said shell.
- 30 6. In combination, a casing adapted to extend circumferentially of an incandescent electric lamp and considerably larger in diameter at one end than at its other end and having an internal annular flange at its diametrically smaller end, an insulating body arranged at the outer side of said flange and having an opening adapted to receive the base of said lamp, a metal shell at the outer end face of said insulating body and insulated from the aforesaid casing and adapted to receive said base through said opening and forming a contact adapted to be engaged by one terminal of said base, a resilient member insulated from said shell and forming a contact adapted to be engaged by the other terminal of said base, and means whereby said resilient member, said shell, the aforesaid insulating body and the aforesaid flange are secured together.
- 35 7. In combination, a casing adapted to extend circumferentially of an incandescent electric lamp and considerably larger in diameter at one end than at the other end and having an internal annular flange at its diametrically smaller end, an insulating body arranged at the outer side of said flange and having an opening adapted to receive the base of said lamp, a metal shell at the outer end face of said insulating body and insulated from the aforesaid casing and adapted to receive said base through said opening and forming a contact adapted to be engaged by one terminal of said base, a resilient member insulated from said shell and forming a contact adapted to be engaged by the other terminal of said base, means whereby said resilient member, said shell, the aforesaid insulating body and the aforesaid flange are secured together, and a removable cap housing said shell and said resilient member and embracing said insulating body and the diametrically smaller end of the aforesaid casing.
- 40 8. The combination, with a casing adapted to extend circumferentially of an incandescent electric lamp, an insulating body arranged externally of and abutting against said casing and having an opening adapted to permit the base of said lamp to extend therethrough, a metal shell arranged and adapted to receive said base through said opening and forming one contact of the socket, and bolts spaced circumferentially of said shell and connected to the aforesaid casing and extending endwise of the socket and through said insulating body, said body being provided at each bolt with a tubular insulating projection which embraces said bolt and is embraced by a portion of said shell, and said bolt extending beyond the outer end of said projection, of an insulating washer mounted on said projection at the outer side of the last-mentioned portion of said shell and thick enough to extend beyond the outer end of said projection, a nut threaded onto said bolt adjacent the outer side of said insulating washer, and a member forming the other contact of the socket and interposed between the nut on one bolt and the adjacent insulating washer and spaced from the aforesaid shell.
- 45 9. The combination, with a metal casing adapted to extend circumferentially of an incandescent electric lamp and having an in-

- 6
- ternal flange at one end, an insulating body arranged at the outer side of said casing-flange and having an opening adapted to receive the base of said lamp, a contact-forming metal shell at the outer end face of said insulating body and arranged and adapted to receive said base through said opening, and spaced bolts connected to the aforesaid flange and extending endwise of the socket 5 at the outer side of said portion of said shell, 45 a nut threaded onto said bolt adjacent the outer side of said washer, and a metal plate between the nut on one bolt and the adjacent washer and spaced from the aforesaid shell and having an integral wing which is arranged between said nut and said shell and terminates in a member engageable by the other terminal of the aforesaid base. 50
- 5 10. The combination, with a casing adapted to extend circumferentially of an incandescent electric lamp, an insulating body externally of and rigid with said casing and having an opening adapted to receive the base of said lamp, a metal shell adapted to receive said base through said opening and 55 forming a contact for one terminal of said base, and spaced bolts connected to the aforesaid casing and extending endwise of the socket, the aforesaid insulating body being provided, at the inner end of said shell adjacent each bolt, with an integral tubular projection which embraces said bolt and is embraced by a portion of said shell, of a rigid insulating washer mounted on said projection at the outer side of said portion 60 of said shell, a nut threaded onto said bolt adjacent the outer side of said washer, and a metal plate between the nut on one bolt and the adjacent washer and having a member engageable by the other terminal of the 65 aforesaid base, the last-mentioned washer having an edge embracing the aforesaid shell, said plate having a flange overlapping another edge of said last-mentioned washer, and the last-mentioned edge and said flange 70 being arranged to prevent displacement of said plate circumferentially of the last-mentioned bolt. 75
10. The combination, with a metal casing adapted to extend circumferentially of an incandescent electric lamp, an insulating body externally of and rigid with said casing and having an opening to receive the base of said lamp, a metal shell at the outer end face of said insulating body and arranged and adapted to receive said base through said opening and forming a contact arranged to be electrically engaged by one 30 terminal of said base, and spaced bolts connected to the aforesaid casing and extending endwise of the socket and through said insulating body, said body being provided, at its outer end face adjacent each bolt, with an 35 insulating tubular projection embracing said bolt and embraced at said face by a portion of said shell, and said bolt extending beyond the outer end of said projection, of an insulating washer mounted on said projection 40

In testimony whereof, I sign the foregoing specification, this 15th day of February, 85 1921.

OSCAR KROEHLER.
